ELECTRIC HAIR CLIPPER

John F. Wahl, Sterling, Ill., assignor to Wahl Clipper Corporation, Sterling, Ill., a corporation of Illinois
Application December 30, 1957, Serial No. 49,055

Term of patent 14 years

(Cl. D22—5)

Fig. 1.

Fig. 2.

Fig. 3.

Fig. 4.

Fig. 1 is a plan view of an electric hair clipper embodying the design;

Fig. 2 is an elevational view of one side thereof; the other side thereof is the same in appearance;

Fig. 3 is a side elevational view like Fig. 2 except that a portion is broken away to illustrate details of the design; and

Fig. 4 is a rear elevational view thereof.

The bottom of the clipper is free of ornamentation.

The essential features of my design reside in the portions shown in solid lines on the drawing.

I claim:

The ornamental design for an electric hair clipper, as shown and described.
